[57] ABSTRACT

A simply operable station selector for television receivers and other communication units. It has a plurality of touch pieces corresponding to respective channels, and a desired channel may be tuned in by merely touching the corresponding touch piece with a finger.

FIG. 5

FIG. 6

FIG. 7

STATION SELECTOR

The invention relates to station selectors for television receivers and other communication units, and it has an object of providing an excellent one-touch station selector with which it is possible to switch over to a desired channel by merely touching a corresponding touch piece.

The invention will now be described in conjunction with some embodiments thereof with reference to the accompanying drawings, in which:

FIG. 1 is a block diagram of one embodiment of the station selector according to the invention;

FIG. 2 is a circuit diagram of part of the embodiment of FIG. 1;

FIG. 3 is a circuit diagram of another part of the embodiment of FIG. 1;

FIG. 4 is a waveform chart for illustrating the operation of the embodiment of FIG. 1;

FIG. 5 is a circuit diagram showing part of another embodiment;

FIG. 6 is a circuit diagram showing part of a further embodiment; and

FIG. 7 is a waveform chart to illustrate the operation of the embodiment of FIG. 6.

Referring to FIG. 1, characters A, B, C, D, E and F with respective subscripts represent 6 different channels. More particularly, characters A and B with subscripts represent respective lower frequency band VHF channels, characters C and D with subscripts represent respective higher frequency band VHF channels, and characters E and F with subscripts represent respective UHF channels. Characters V_T, V_S, V₁ and V₂ represent output terminals which are connected to an electronic tuner (using variable capacitance diodes). A tuning voltage to be impressed upon a variable capacitance diode appears at the terminal V_T, a switching voltage to be impressed upon a switching diode for switching frequency bands appears at the terminal V_S, a source voltage to be supplied to the r-f amplifier stage and local oscillator stage of VHF tuner appears at the terminal V₁, and a source voltage to be supplied to a UHF tuner appears at the terminal V₂. The mixer stage of the VHF tuner always receives the source voltage. The i-f output signal of the UHF tuner is applied to the mixer stage of the VHF tuner to let the mixer stage act as an amplifier stage.

In FIG. 1 blocks designated by characters with the same subscript have the same circuit construction. Accordingly, as a typical example blocks A₁ to A₆ for channel A will now be described. Character A₁ designates a touch piece which is made of a conductor and bears an indication of the channel number. For tuning in the corresponding channel, i.e., channel A, it is touched with part of the human body (such as a finger). The block A₂ includes a generator to generate a signal when the touch piece is touched with part of the human body, and an amplifier and a shaping circuit to produce a signal to be coupled to the next stage memory A₄. When the touch piece A₁ is touched with a finger, the circuit A₂ produces an output signal to drive the memory A₄ which consists of a flip-flop. The output of A₂ is also coupled to the blocks B₃, C₃, D₃, E₃ and F₃. The memory A₄ functions such that when it directly receives the output of A₂ it causes the succeeding stage block A₆ to provide a tuning voltage and that when it receives the output of any other block than A₂, for in-

stance block B₂, through an OR reset circuit of block A₃ and a terminal f it causes the tuning voltage generating circuit A₆ to provide no tuning voltage. The OR gate of the block A₃ allows an input signal appearing at any one of its input terminals to be passed to the terminal f. The block A₅ is an impedance converter for transmitting the output of the block A₄ to the succeeding stage as a control signal. For example, it may be a high input, low output impedance circuit such as an emitter follower. It may be dispensed with if the output impedance of the block A₄ is low enough.

The block A₆ comprises a gate section and a tuning voltage generating section. The gate section functions such that if a signal prevails at one input terminal e of the block A₄ the tuning voltage for channel A is provided while if a signal prevails at the other input terminal f no tuning voltage is provided from the block A₄. As mentioned earlier, the blocks for the other channels have the same constructions as the corresponding blocks described above for channel A. A block M selectively transmits the tuning voltage of any one channel to its output V_T, and it functions as a kind of OR circuit.

It is now assumed that channel A is tuned in and the tuning voltage for channel A prevails at the terminal V_T. Then, if touch piece D₁, for instance, is touched with a finger to switch over to channel D, the block D provides an output signal to the block D₄ and also to the blocks A₃, B₃, C₃, E₃ and F₃. When the blocks A₃, B₃, C₃, E₃ and F₃ receive a signal, the respectively associated tuning voltage generating circuits gate such that the tuning voltages for the respective channels are not provided. Thus, the tuning voltage at the output of A₆ disappears due to the signal delivered from D₂ to A₃. Similar actions are also provided for the other channels B, C, E and F. Meanwhile, upon reception of the signal from D₂ the memory of block D₄ acts to cause the block D₆ to provide the tuning voltage for channel D, which is supplied to the block M and appears at the output terminal V_T.

The station selector of FIG. 1 further includes blocks G, H, I, J, K and L. The block H has its output terminal V_S, at which there appears a switching voltage impressed upon a switching diode in the electronic tuner. The switching voltage must assume either a constant positive level or a constant negative level, for instance with the negative level for the lower frequency band and the positive level for the higher frequency band of the VHF band. The block H comprises a gate section and a switching section for switching between positive and negative source voltages under the control of the gate section. If no control signal is present at the input of the block H a positive voltage is available at the output terminal V_S, while when a control signal is present at the input a negative voltage is available at the output. The block G is an OR gate, and it passes a control signal appearing at either one of its input terminals to the block H.

With this arrangement, a negative voltage appears at V_S when a lower frequency band VHF channel A or B is selected, while a positive voltage appears when a higher frequency band VHF channel is selected, so that the switching diode may be operated accordingly.

The block J has its output terminal V₁, at which appears a source voltage supplied to the r-f amplifier stage and local oscillator stage of VHF tuner. The source voltage appears at V₁ only when a VHF channel

is selected. When a UHF channel is selected, no source voltage appears at V_1 so that the *r-f* amplifier stage and local oscillator stage of the VHF tuner are inoperative.

The block L has its output terminal V_2 , at which appears source voltage supplied to UHF tuner. The source voltage appears at V_2 only when a UHF channel is selected. When a VHF channel is selected, no source voltage appears at V_2 so that the UHF tuner is inoperative. The block L may thus have the same circuit construction as the block J, and the gate section of each of these blocks may be arranged to function such that the source voltage is available in the presence of the control signal and is not available in the absence of the control signal.

The blocks I and K are OR gates that pass a control signal that may appear at one of their input terminals to their associated block J or L. With this arrangement, when a VHF channel is selected the source voltage appears at V_1 , to render the VHF tuner operative but no source voltage appears at V_2 so that the UHF tuner is inoperative. Conversely, when a UHF channel is selected, the *r-f* amplifier stage and local oscillator stage of the VHF tuner are held disabled and only the mixer stage of the VHF tuner and the UHF tuner are rendered operative. In this manner, a desired channel may be tuned in.

It will be apparent from the above description in connection with a typical channel-changing operation that the present invention makes it possible to electronically effect the selection of any one of a number of television channels (as for example, three low-frequency VHF channels 1-3, nine high-frequency VHF channels 4-12 and UHF channels 13-62, such as are used in Japan).

A specific embodiment of the invention is shown in FIGS. 2 and 3. In FIG. 2, the individual blocks are designated by the same reference symbols as in FIG. 1. Block A_2 which is a detecting circuit comprises an oscillator, a circuit to change the amplitude of the oscillator output, a detector, an amplifier and a shaping circuit. The oscillator consists of transistor TR_1 , and its frequency of oscillation is substantially determined by the inductance of L_1 and capacitance of C_1 . When a touch piece in block A_1 is touched with a finger, the oscillator output is divided between capacitance C_1 and a capacitance between the touch piece and the finger in contact therewith, so that the amplitude of the oscillator output at point a , is reduced as shown in curve a in FIG. 4. The period t between t_1 and t_2 during which the touch piece is touched with a finger may be either comparatively long or almost momentary. During this period the amplitude is reduced.

The detector consisting of diode D_{11} detects the oscillator output. When the touch piece is touched with finger, the voltage at point b is increased as shown at b in FIG. 4, whereupon transistor TR_2 is turned conductive. If the touch piece is not touched, the voltage at point b is low and the transistor TR_2 remains "off." The waveform of the voltage at point b is of integral type and has inclined rising and falling portions. Therefore, the voltage waveform at point c also has corresponding inclined rising and falling portions. Since the next stage memory section uses a T-type flip-flop, it is necessary to provide a waveform without any inclined portion and having a sharp transient characteristic for producing a trigger pulse. Accordingly, the output signal at point c is coupled to a Schmitt trigger circuit of transistors TR_3 and TR_4 for converting the signal waveform

into the one having a sharp transient characteristic, as shown at d in FIG. 4. The waveform thus provided for point d is then differentiated through capacitor C_3 to produce a trigger pulse for the next stage flip-flop of transistors TR_5 and TR_6 , as shown at e in FIG. 4. If a negative pulse is produced as the trigger pulse, touching of the touch piece A_1 with a finger causes an action of the flip-flop to be described hereinafter. If a positive pulse is to be provided, diodes D_{11} and D_{12} and diodes $D_{51}, D_{52}, \dots$ in block A_3 may be oppositely connected in respect of their polarity. By so arranging, a positive pulse will appear upon touching the touch piece with a finger. In this case, it is necessary to alter the connection so that the signal appearing at point e is coupled to the collector of the transistor TR_5 and the signal appearing at point f to the collector of the transistor TR_6 .

In the operation of the flip-flop in block A_4 , upon appearance of a negative pulse at point e the transistor TR_5 is cut off while the transistor TR_6 is turned conductive and saturated. As a result, at the instant $t = t_1$ the voltage at point g is reduced to nearly the earth potential, as shown at g in FIG. 4, cutting off transistor TR_8 so that a tuning voltage which is preset with variable resistor VR_1 appears at point h , as shown at h in FIG. 4. With the tuning voltage appearing at point h the corresponding diode D_{21} in the OR circuit of block M is rendered conductive (with all the other diodes in block M rendered "off"), whereupon the tuning voltage preset with VR_1 for channel A appears at V_7 and is coupled to the electronic tuner to select channel A.

Meanwhile, with the reduction of the voltage at point g a diode D_{31} in the OR circuit of block G is activated to trigger and saturate gate circuit transistor TR_{10} in block H , thus also saturating transistor 11 . As a result of saturation of the transistor TR_{11} , its collector potential becomes substantially equal to its emitter potential, so that a negative voltage (V_{CC_4}) appears at V_s . With the negative voltage at V_s the electronic tuner selects a lower frequency band VHF channel.

Also, with the reduction of the voltage at point g a diode D_{41} in the OR circuit of block I is activated to cut off gate circuit transistor TR_{12} to trigger transistor TR_{13} in the flip-flop of block J . The transistor TR_{13} has its base connected through a resistor to its collector so that a voltage slightly lower than its collector voltage V_{CC_3} appears at its emitter (since upon the triggering of the transistor TR_{13} it is saturated or nearly saturated). Upon appearance of a voltage at terminal V_1 the VHF tuner is rendered operative since the source voltage is impressed on the *r-f* amplifier stage and local oscillator stage of the VHF tuner and it is always applied to the mixer stage. At this time the tuning voltages of the other channels do not appear at the input of the block M in view of point j being connected to the blocks B_3, C_3, D_3, E_3 and F_3 in FIG. 1.

It will be appreciated from the foregoing that by touching the touch piece A_1 with a finger the lower frequency band VHF channel A can be selected.

Now if another channel, for instance channel C, is to be selected, the touch piece C_1 is touched with a finger. Then, the same action as described above for the blocks A_2, A_4, A_5, A_6, I and J takes place in the blocks C_2, C_4, C_5, C_6, I and J , and a tuning voltage for channel C appears at the output of the block C_6 to activate the corresponding diode in the block M so that the tuning voltage for channel C appears at the terminal V_7 .

Meanwhile, the output of the block C_2 also appears at block A_3 , causing a negative trigger pulse to appear at point f through the channel C diode in the OR reset circuit A_3 , thus inverting the flip-flop in block A_4 , that is, triggering TR_5 and cutting off TR_6 , so that a voltage substantially equal to V_{CC_1} appears at point g . With the increase of voltage (substantially equal to V_{CC_1}) at point g the gate circuit transistor TR_8 in block A_8 is saturated. As a result, the voltage at point h disappears (or is substantially reduced to the earth potential) to cut off diode D_{21} in block M . Thus, only the tuning voltage for channel C appears at terminal V_T .

Also, with the increase of voltage at point g diode D_{31} in block G is cut off. Since the other diode D_{32} in block G (which diode is connected to the block B_5 in FIG. 1) is "off" (for the output voltage of B_5 is high like the output of A_5), the gate circuit transistor TR_{10} in block H is cut off to cut off the transistor TR_{11} , so that a voltage (set to a positive value) as a division of voltage $V_{CC_1} - V_{CC_4}$ between resistors R_1 and R_2 appears at terminal V_S . With the positive voltage appearing at terminal V_S a switching diode in the electronic tuner is activated so that a higher frequency band VHF channel may be selected.

Further, with the increase of voltage at point g the diode D_{41} in block I is cut off while another diode D_{43} which is connected to the block C_5 is activated so that the transistors TR_{12} and TR_{13} remain in the same state as when channel A is tuned in. Thus, a voltage slightly lower than V_{CC_3} appears at V_1 , thus rendering the VHF tuner operative.

To summarize the description so far, by touching the touch piece C_1 with a finger the VHF tuner is rendered operative to be ready to select a higher frequency band VHF channel, while the tuning voltage for channel C which is one of the higher frequency band VHF channels appears at terminal V_T , so that the channel C is selected.

The case of selecting a UHF channel, for instance channel E , will now be considered.

Upon touching the touch piece E_1 with a finger the same sequence of events as described earlier for the blocks A_2 , A_3 , A_5 and A_6 takes place in the blocks E_2 , E_4 , E_5 and E_6 , causing a tuning voltage for channel E to appear at the tuning voltage terminal V_T . As a result, a diode in block M corresponding to channel E is activated while the other diodes remain "off." Also, both the diodes in block G are rendered "off" (since the blocks A_5 , B_5 , C_5 and D_5 all provide a positively high voltage). As a result, the gate transistor TR_{12} in block J is saturated so that its collector voltage becomes substantially equal to its emitter voltage, thus cutting off the transistor TR_{13} to render the voltage at V_1 to the earth potential. When the potential of V_1 is reduced to the earth potential, the $r-f$ amplifier stage and local oscillator stage of the VHF tuner are disabled so that no VHF channel can be tuned in. Thus, only the mixer stage of the VHF tuner which receives the $i-f$ signal from the UHF remains operative.

The blocks K and L respectively have the same circuit constructions as the blocks I and J , as shown in FIG. 3. In operation, when the output of block E_5 or F_5 is reduced nearly to the earth potential, that is, when channel E or F is selected, diode D_{61} or D_{62} is activated to cut off transistor TR_{14} and trigger transistor TR_{15} , thus causing a voltage to appear at V_2 . Since the terminal V_2 is the power supply terminal for the UHF tuner,

the UHF tuner is rendered operative. When the output of the block E_5 or F_5 is increased to a high level, that is, when either channel A , B , C or D is selected, the diodes D_{61} and D_{62} are all rendered "off" to cause saturation of transistor TR_{14} , thus rendering the voltage at V_2 to the earth potential to render the UHF tuner inoperative.

As has been described, the station selector of the above construction, when combined with an electronic tuner, enables switching to a desired channel with one-touch operation. Also, since mechanical parts involved are very few, yield and reliability can be increased.

As for the detecting circuit A_2 described above in connection with FIGS. 2 and 4 and which detects the change of amplitude of the oscillator output, certain alternatives can be considered, namely one which utilizes the surface leak resistance of human body and one having resort to a superimposed hum voltage.

FIG. 5 shows an alternative of the detecting circuit which utilizes the surface leak resistance (100 kilohms to 3 megohms) of the human body. In the Figure, numerals 1 and 2 designate electrodes to be touched with finger. When the electrodes 1 and 2 are touched with a finger, the base potential of transistor 3 is reduced due to the leak resistance of the human body to change the conductivity of the transistor. As a result, the emitter potential on the transistor 3 is reduced to cause inversion of a Schmitt circuit of transistors 4 and 5. The output of the Schmitt circuit is coupled through a capacitor 6 to the next stage flip-flop A_4 and OR gates B_3 , C_3 , D_3 , E_3 and F_3 , and the following sequence is the same as for the embodiment of FIG. 2.

FIG. 6 shows another alternative of the detecting circuit which has resort to a hum voltage. In the Figure, numerals 7 and 8 designate terminals between which a hum voltage is impressed via a source transformer or a capacitance or resistance connected between the primary and secondary of the source transformer. Numeral 9 designates a detecting transistor, numerals 10 and 11 transistors constituting a Schmitt trigger circuit, numeral 12 an output terminal connected to the next stage flip-flop A_4 and OR gates B_3 , C_3 , D_3 , E_3 and F_3 , and numeral 13 a base resistance for the transistor 9.

In operation, upon touching the touch piece A_1 with a finger a hum voltage as shown at i in FIG. 7 is generated across the resistor 13 due to the impedance of the human body with respect to the earth. The hum voltage thus generated is amplified by the transistor 9 and rectified by resistor 14 and capacitor 15 connected to the collector of the transistor 9 to produce a signal as shown at j in FIG. 7. With this rectified signal the Schmitt trigger circuit is inverted. In this manner, a signal as shown at k in FIG. 7 appears at the output terminal 12, so that the signal as shown in FIG. 2 may be provided to the succeeding stages for the switching of channels.

While the foregoing embodiment has concerned with television receivers, similar arrangements for use in other communication units such as radio sets may be obtained in accordance with the invention.

What is claimed is:

1. A one-touch controllable channel selector for use with an electronic tuner having variable capacitance diodes comprising: touch pieces to be touched by a part of the human body and corresponding respectively to channels to be tuned in; detector circuits connected to said touch pieces, respectively, for detecting the touch

of the human body on the respective touch pieces, each detector comprising a signal generator for generating a touch signal at the time of said touch, an amplifier for amplifying the touch signal and a waveform converting circuit for converting an output from said amplifier into a trigger signal; memory circuits connected to said detectors, respectively, and controlled by the respective trigger signals; circuit means connected to said memory circuits, respectively, and to said detector circuits to reset the corresponding memory circuit by the trigger signal supplied from the detector circuits other than the corresponding detector circuit; and gate circuits controlled by the respective memory circuits, said gate circuits each supplying a channel selecting voltage, a band switching voltage and a power voltage to said variable capacitance diodes in response to the corresponding memory circuit.

2. A selector according to claim 1, wherein said signal generators each comprises an oscillator to generate a signal at a given frequency, a circuit furnished with the signal output of said oscillator, the amplitude of the output of said last-mentioned circuit being changed when the corresponding touch piece is touched by part of the human body, and a detector to detect the output of said last-mentioned circuit.

3. A selector according to claim 1, wherein said signal generators each comprises a detecting transistor, the base potential of said detecting transistor being changed when the corresponding touch piece is touched by a part of the human body, and a threshold discriminator to detect a change in the conductivity of said detecting transistor.

4. A selector according to claim 1, wherein said detecting circuits each comprises a circuit to form a closed current loop including the corresponding touch piece, said closed current loop being formed when said corresponding touch piece is touched by part of the human body, and a detector to detect a change in the

terminal voltage across an impedance element inserted in said closed current loop.

5. A selector according to claim 1, wherein said memories each consists of a flip-flop set by the output of the associated signal generator circuit and reset by the output of any other one of said control circuits than the one associated to said associated signal generator circuit.

6. A channel selector, comprising:
 a plurality of touch pieces corresponding to respective channels to be tuned;
 a plurality of detecting circuits individually coupled to corresponding touch pieces for providing an output signal when the corresponding touch piece is touched by a portion of the human body, said detecting circuits each comprising an oscillator circuit for generating a signal at a given frequency, an amplitude changing circuit, the amplitude of which varies when the corresponding touch piece is touched, and means for detecting the change in amplitude of the output of said amplitude changing circuit;
 a plurality of memory means coupled to respective ones of said detecting circuits;
 a plurality of control circuits individually coupled to the reset inputs of respective ones of said memory means, said control circuits also being coupled to each of said detecting circuits other than the one coupled to the respective one of said memory means to which that control circuit is coupled;
 a plurality of gate circuits individually coupled to respective outputs of said memory means;
 circuit means coupled to and controlled by said gate circuits for selectively providing tuning voltages to channel determining variable capacitance diodes in an electronic tuner and for providing frequency band and voltage source switching signals.
